US0D1086970S

(12) **United States Design Patent** (10) **Patent No.:** **US D1,086,970 S**
(45) **Date of Patent:** **** Aug. 5, 2025**

(54) **AERIAL VEHICLE**

(71) Applicant: **Amazon Technologies, Inc.**, Seattle, WA (US)

(72) Inventors: **Louis Leroi LeGrand, III**, Seattle, WA (US); **Gur Kimchi**, Seattle, WA (US); **Dominic Timothy Shiosaki**, Seattle, WA (US); **Ricky Dean Welsh**, Seattle, WA (US)

(73) Assignee: **Amazon Technologies, Inc.**, Seattle, WA (US)

(**) Term: **15 Years**

(21) Appl. No.: **29/774,566**

(22) Filed: **Mar. 17, 2021**

Related U.S. Application Data

(60) Division of application No. 29/638,993, filed on Mar. 2, 2018, now Pat. No. Des. 916,623, which is a continuation of application No. 29/624,129, filed on Oct. 30, 2017, now Pat. No. Des. 942,921.

CLAIM

The ornamental design for an aerial vehicle as shown and described.

DESCRIPTION

FIG. 1 is a top view of an aerial vehicle.

FIG. 2 is a perspective view of the aerial vehicle of FIG. 1.

FIG. 3 is a left side view of the aerial vehicle of FIG. 1.

FIG. 4 is a front view of the aerial vehicle of FIG. 1.

FIG. 5 is a right side view of the aerial vehicle of FIG. 1.

FIG. 6 is a rear view of the aerial vehicle of FIG. 1; and,

FIG. 7 is a bottom view of the aerial vehicle of FIG. 1.

The evenly spaced broken lines in the drawings depict portions of the aerial vehicle that form no part of the claimed design. The dot-dash broken lines in the drawings depict environmental subject matter only and form no part thereof.

1 Claim, 7 Drawing Sheets
